COMBINED VASE AND CABINET

David S. Boyer, Albany, N. Y.

Application November 18, 1953, Serial No. 27,660

Term of patent 7 years

(Cl. D33—3)

Fig. 1

Fig. 2

Fig. 3

Fig. 4

Fig. 1 is a front elevation view of a combined vase and cabinet showing my new design.

Fig. 2 is a right hand side elevation view;

Fig. 3 is a top plan view; and

Fig. 4 is a perspective view thereof.

I claim:

The ornamental design for a combined vase and cabinet, as shown.
